UNITED STATES PATENT OFFICE.

HENRY C. BEARD, OF SOUR LAKE, TEXAS, ASSIGNOR OF ONE-HALF TO MRS. N. A. CRAVENS, OF SILSBEE, TEXAS.

TANK THIEF.

Application filed May 2, 1924. Serial No. 710,677.

To all whom it may concern:

Be it known that I, HENRY C. BEARD, a citizen of the United States, residing at Sour Lake, in the county of Hardin and State of Texas, have invented new and useful Improvements in Tank Thieves, of which the following is a specification.

This invention relates to implements used for extracting a sample of liquid from a receptacle and has for its object the provision of a novel tank thief adapted to be lowered to any desired depth in a receptacle and provided with valve means for trapping a sample of the liquid.

An important and more specific object is the provision of a device of this character embodying a novel valve structure and manually operable releasing means therefor whereby to effect closing of the device at a desired level within the tank or other container.

The invention further contemplates the general improvement in the various details of construction and arrangement whereby to produce a device for the purpose specified which will be simple to manufacture, easy to use and operate, positive in action, and durable in service.

With the above and other objects and advantages in view the invention consists in the details of construction to be hereinafter more fully described and claimed and illustrated in the accompanying drawings, in which:

Figure 1 is a side elevation of the device, Figure 2 is an elevation of the lower end on a considerably larger scale,

Figure 3 is an elevation at right angles to Figure 2 showing the valve open.

Referring more particularly to the drawings the numeral 10 designates an elongated glass tube located within a protective cage including a ring 11 to which are secured elongated strips 12 which are curved in cross section to conform to the tube and which are connected at intervals by cross members 13. The upper ends of the strips 12 project beyond the top of the glass tube and are connected by a suspension loop 14 to which is connected a cord or other flexible member 15 by means of which the device may be lowered into an oil tank or the like. One strip 12, or both if preferred, is provided with graduations 16.

Secured upon the ring 11 are double

guides 17 including inner open channels 18 and outer closed channels 19. For closing the lower end of the tube, I provide a valve comprising a disk 20 carrying a packing 20^a and provided with spaced parallel arms 21 having their free ends located within the open channels 18 and pivotally mounted therein by pivot pins 22 passing through the open channels and through slots 23 in the arms. By this construction it will be seen that this valve is free to swing into or out of obstructing relation to the lower end of the ring 11. The slots 23 are important as they permit the valve to be brought up snugly to seal the lower end of the device 70 and retain a sample therein.

Carried by the disk 20 is an elongated leaf spring 24 which is disposed against and movable along a guide strip 25 mounted at one side of the cage. At its free end 75 this leaf spring carries an eye 26.

Mounted below the valve device above described is a ring 27 carried by spaced parallel arms 28 which are slidable through the closed channels 19 and to which are connected coil springs 29 engaged upon hooks 30 or the like at opposite sides of the cage. This ring 27 is adapted to be held in spaced relation to the bottom of the device by means of a pivoted catch 31 which operates as will 85 be described.

The valve releasing means comprises a pair of angularly shaped arms 32 pivoted at 33 on the strip 25 and terminating at one end in extensions 34 and at their other ends 90 in jaws 35. A spring is provided for normally holding these arms in such position that the jaws 35 will be in contact. When the valve is open, the eye 26 is engaged between the jaws 35 for positively holding 95 the valve against closing movement, the catch 31 holding the disk 27 spaced away from the lower end of the device.

To effect release of the valve, I provide 100 an elongated plunger 37 slidable through suitable guides 38 on the cage and also slideable through an ear 39 at the upper end of the strip 25. This plunger has its upper end formed with a lateral extension 40 to which is connected the flexible member 15 105 so that it may be manipulated by the operator, and the lower end of the plunger is formed with a wedge shaped head 42 adapted to be forced between the extensions 34 for swinging the arms 32 and releasing 110

the jaws 35 from engagement with the eye 26. A cushion spring 43 is provided on the plunger for normally holding it in retracted position.

• In case the device is to be used in obtaining samples from an oil tank containing a large quantity of B. S. it may be necessary to provide one or more weights 44 which may be secured on the cage at any desired 10 points and which will operate to insure passage of the device down through this heavy matter.

In the operation, it is first necessary to open the device and this is done by pulling 15 the disk 27 downwardly and swinging the catch 31 into engagement therewith so that the disk will be positively held in spaced relation to the lower end of the ring 11 with the springs 29 under tension. The valve 20 20 is then swung laterally and into substantially vertical position and out of obstructing relation to the lower end of the ring. The leaf spring 24 is thus placed under tension. The eye 26 is engaged between the jaws 25 25 and they will operate to hold this valve positively in its open position. The device is then lowered into the tank from which the sample is to be extracted, the flexible member 15 permitting lowering. When the 30 device has been sunk to the desired depth, a small weight W is slipped over or onto the flexible member 15 and allowed to descend therealong. When this weight strikes against the lateral extension 40, the plunger 35 35 will be moved downwardly against the resistance of the spring 43 and the wedge shaped head 42 will be forced between the extensions 34 of the valve holding arms. When this occurs the jaws 35 move apart 40 and the eye 26 is released, thus permitting the spring 24 to throw the valve 20 into its normal position below the lower end of the ring 11. The edge of this valve will strike against the catch 31 and unseat it so that the 45 springs 29 will pull the ring 27 upwardly into forcible engagement with the valve, thus holding it firmly against the ring 11 and making an effective seal which will hold the liquid which has entered the tube during 50 its descent in the tank. By pulling upon the flexible member 15 the device is then lifted out of the tank.

While I have shown and described the preferred embodiment of my invention it 55 is of course to be understood that I reserve the right to make such changes in the form, construction and arrangement of parts as will not depart from the spirit of the invention or the scope of the subjoined claims.

60 I claim:

1. A device of the character described comprising an elongated tube provided with suspension means, a valve pivoted at the lower end of the tube and adapted to close 65 the same, an elongated leaf spring carried

by one edge of said valve and located against one side of the tube, means engaging said spring for holding the valve open and including a pair of arm members pivoted in cross relation and terminating at one end in 70 jaws for engaging the spring and terminating at the other end in extensions, and means for forcing said extensions apart to release the spring.

2. A device of the character described comprising 75 an elongated tube provided with suspension means, a valve pivoted at the lower end of the tube and adapted to close the same, an elongated leaf spring carried by one edge of said valve and located against 80 one side of the tube, a device engaging said spring for holding the valve open and including a pair of arm members pivoted in crossed relation and terminating at one end in jaws engaging the spring and terminating at the other end in extensions, and means for forcing said extensions apart to release the spring comprising a plunger slidably mounted through guides on the tube and having a wedge shaped head adapted to be 85 forced between said extensions.

3. A device of the character described comprising an elongated tube provided with suspension means, a laterally swingable valve pivoted at the lower end of the tube 95 and adapted to close the same, an elongated leaf spring carried by one edge of said valve and located against one side of the tube, means engaging said spring for holding the valve open and including a pair 100 of jaw members, and means for forcing said jaw members apart to release the spring, an upwardly spring moved member slidably mounted at the lower end of the tube and adapted to engage and seat the valve when 105 said spring is released, and means normally holding said last named member inoperative.

4. A device of the character described comprising an elongated tube provided with suspension means, a valve pivoted at the 110 lower end of the tube and adapted to close the same, an elongated leaf spring carried by one edge of said valve and located against one side of the tube, a clamp device engaging said spring for holding the valve open and including a pair of arm members pivoted in cross relation and terminating at one end in 115 jaws for engaging the spring and terminating at the other end in extensions, and means for forcing said extensions apart to release the spring, an upwardly spring moved member slidably mounted at the lower end of the tube and adapted to engage and seat the valve when said spring is released, means 120 normally holding said last named member inoperative, consisting of a pivoted catch located in the path of movement of the valve and released upon engagement thereby.

In testimony whereof I affix my signature.

HENRY C. BEARD.
